[57] **CLAIM**

The ornamental design for a stackable jar set, as shown and described.

DESCRIPTION

FIG. 1 is a perspective view from above showing our new design;

FIG. 2 is an exploded perspective view thereof;

FIG. 3 is a top plan view thereof;

FIG. 4 is a front elevational view thereof, the rear and side elevations are the same; and,

FIG. 5 is a bottom plan view thereof.

The broken lines in FIG. 2 showing the neck portions of the jars are for illustrative purposes only and form no part of the claimed design.
